CLAIM

The ornamental design for WRENCH as shown and described.

DESCRIPTION

FIG. 1 is a front perspective view from above of an embodiment of the claimed design;

FIG. 2 is a front perspective view from below of the claimed design of FIG. 1;

FIG. 3 is a rear perspective view from above of the claimed design of FIG. 1;

FIG. 4 is a front view of the claimed design of FIG. 1;

FIG. 5 is a rear view of the claimed design of FIG. 1;

FIG. 6 is a left side view of the claimed design of FIG. 1;

FIG. 7 is a right side view of the claimed design of FIG. 1;

FIG. 8 is a top view of the claimed design of FIG. 1;

FIG. 9 is a bottom view of the claimed design of FIG. 1;

FIG. 10 is a front perspective view from above of another embodiment of the claimed design;

FIG. 11 is a front perspective view from below of the claimed design of FIG. 10;

FIG. 12 is a rear perspective view from above of the claimed design of FIG. 10;

FIG. 13 is a front view of the claimed design of FIG. 10;

FIG. 14 is a rear view of the claimed design of FIG. 10;

FIG. 15 is a left side view of the claimed design of FIG. 10;

FIG. 16 is a right side view of the claimed design of FIG. 10;

FIG. 17 is a top view of the claimed design of FIG. 10;

FIG. 18 is a bottom view of the claimed design of FIG. 10;

FIG. 19 is a front perspective view from above of another embodiment of the claimed design;

FIG. 20 is a front perspective view from below of the claimed design of FIG. 19;

FIG. 21 is a rear perspective view from above of the claimed design of FIG. 19;

FIG. 22 is a front view of the claimed design of FIG. 19;

FIG. 23 is a rear view of the claimed design of FIG. 19;

FIG. 24 is a left side view of the claimed design of FIG. 19;

FIG. 25 is a right side view of the claimed design of FIG. 19;

FIG. 26 is a top view of the claimed design of FIG. 19;

FIG. 27 is a bottom view of the claimed design of FIG. 19;

FIG. 28 is a front perspective view from above of another

(Continued)

embodiment of the claimed design;
 FIG. 29 is a front perspective view from below of the claimed design of FIG. 28;
 FIG. 30 is a rear perspective view from above of the claimed design of FIG. 28;
 FIG. 31 is a front view of the claimed design of FIG. 28;
 FIG. 32 is a rear view of the claimed design of FIG. 28;
 FIG. 33 is a left side view of the claimed design of FIG. 28;
 FIG. 34 is a right side view of the claimed design of FIG. 28;
 FIG. 35 is a top view of the claimed design of FIG. 28; and
 FIG. 36 is a bottom view of the claimed design of FIG. 28.
